VARIABLE RESISTOR CONSTRUCTION

Raymond W. Searle, Waltham, and Lauren M. Burgess, Lexington, Mass., assignors to Technology Instrument Corporation, Acton, Mass.

Application April 20, 1951, Serial No. 222,016

4 Claims. (Cl. 201—48)

1

The present invention relates to an improved variable resistor construction and the method of assembly thereof.

In the manufacture of precision variable resistors, generally called potentiometers, particularly suited for servo mechanisms, it is necessary to provide a construction which has stable characteristics not affected by changes in temperature and humidity. In the construction of such variable resistors substantially all parts thereof are coated with varnish and baked. Due to the temperature of the baking process certain precautions must be taken to insure retaining the resistance element in position.

It therefore is an object of the present invention to provide an improved variable resistor construction and method of assembly.

A still further object of the present invention is to provide an improved variable resistor having means for retaining in position the variable resistance element during its manufacture and throughout the useful life of the resistor.

Other and further objects of the present invention subsequently will become apparent by reference to the following description taken in conjunction with the accompanying drawing; wherein

Figure 1 is an end view of a variable resistor, with the cover removed, constructed in accordance with the present invention;

Figure 2 is a cross-sectional view of a variable resistor shown in Figure 1 as seen in the direction of the arrows along the line 2—2; and

Figure 3 is a perspective view of the retaining ring element employed in the resistor of Figures 1 and 2.

Referring to the drawing, the resistor construction illustrated employs a cylindrical casing 11 having a cylindrical wall 12 and an end wall 13. The end wall 13 is provided with a boss 14 for supporting a bearing 15 for a shaft 16. The bearing 15 has a threaded end 17 for receiving a mounting nut for holding the variable resistor in position on an apparatus. The shaft 16 is provided with a groove into which is fitted a split ring 18 which engages the end of the bearing member 15. The shaft 16 at its other end carries a split sleeve 19 which is engaged by an arm 21. The arm 21 at its lower end is provided with bifurcated portions 22, which may be drawn together by a stud bolt 23 passing through a suitable aperture in one of the bifurcated portions and engaging a threaded aperture in the other bifurcated portion 22. At its outer end the arm 21 has a threaded opening for receiving a screw 55

2

24 which engages a contact assembly 25 having an outwardly extending arm 26, which carries a precious alloy contact element 27. The precious alloy contact element 27 engages the turns of resistance wire on a resistance element. The contact assembly 25 also includes two similar brush arms 28, each provided with a precious alloy contact 29 which engages a slip ring 31. The slip ring 31 is mounted on an insulated bushing 32, which fits over the bearing boss 14 of the end wall 13 and the end portion of the bearing sleeve 15. A slip ring 31 is suitably connected to the center terminal 32 of a plurality of terminals carried by a terminal block 33 mounted on the outside of the casing 11.

Mounted within the casing 11 adjacent the inside of the cylindrical wall 12 is a resistance element 34 formed of a flat strip of insulating material about which has been wound in spaced relation a resistance wire 35. The ends of the resistance wire 35 are connected to electrical terminals 36 and 37 carried by the terminal block 33. In order to assure retaining the resistance element 34 in position during the assembly and during the useful life of the variable resistor, there is provided a retaining ring 38, which is shown in perspective in Figure 3.

This split retaining ring 38 is positioned against the end wall 13 of the housing and against the resistance element 34. The split ring 38 is expanded by a wedge 39 which engages the split of the ring, and which is provided with a central aperture 41. The central aperture 41 receives a screw 42 which engages a threaded opening 43 in the end wall 13 of the housing 11. The housing 11 is provided with a cover 44, which is provided with a vent or aperture 45.

In order to assemble the device heretofore described so as to provide stable characteristics not affected materially by variations in temperature and humidity, the following method of manufacture is employed. All insulating material elements, such as the resistance element strip 34, the insulated sleeve 32, and the retaining ring 38, together with its wedge 39, are baked for about one-half hour in an oven at approximately 212° F. to drive off all possible moisture. Thereafter all exposed surfaces of these insulated elements are varnished. The entire inside of the housing 11 is also varnished. These elements are then baked in a well ventilated oven for several hours at a temperature of 275° F.

Thereupon the slip ring bushing 32 is inserted into the varnished base, the slip ring 31 is placed in position, then insulating members are inserted

to line the inside cylindrical wall 12 and the back end wall 13. These insulating members are varnished into position and a suitable varnish is employed. The varnish is then applied to the exposed edges of the slip ring insulating bushing both above and below the slip ring with a slight overlap of the varnish into the slip ring. This is then baked for several hours at a temperature of 275° F.

Previous to assembling other elements of the variable resistor, the resistance wire supporting strip 34 has been varnished and baked. Resistance wire is applied thereto and suitably secured in position. The brush arm assembly is mounted on a dummy shaft and all exposed surfaces of the assembly are carefully painted with varnish, except for the precious metal contacts 27 and 29. This is also baked at a temperature of 275° F. for approximately two hours. At the same time the inside of the cover 44 is varnished and likewise baked for a similar time at the same temperature. The terminals 32, 36 and 37 are pressed into the mounting plate 33 and varnished into position.

Thereafter, the resistance element strip 34 is varnished with exception of a buffed track for the brush arm. While the varnish is still wet, the resistance element is inserted into the housing 11. The ring 38 and its wedge 39 are again varnished and then placed into position within the casing 11. Additional varnish is applied at the place where the ring 38 engages the resistance element 34. The terminal plate 33 is coated with the varnish and mounted in position. Varnish is now applied to the outside of the casing 11, including the bushing 15 up to the point where the threads 17 begin. This is then baked for several hours at a temperature of 275° F.

Next, electrical connections are completed to the terminals of the resistance wire 35 and to the slip ring 31. The brush arm assembly is then installed on the end of the shaft 16. The exposed end of the shaft is varnished and varnish is extended over the brush arm 21. Varnish is applied at the fitting edges on both the cover and the base whereupon the cover is pressed into position. The entire outside surface of the cover and the edges of the housing 11 are varnished. This is then again baked at a temperature of 275° F. for approximately two hours.

To illustrate the application of varnish to the various surfaces, double lines have been used in Figures 1 and 2.

While for the purpose of illustrating and describing the present invention a particular embodiment has been shown in the drawing, it is to be understood that the invention is not to be limited thereby, since such variations in construction and in assembly are contemplated as may be commensurate with the spirit and scope of the invention defined in the accompanying claims.

We claim as our invention:

1. In a variable resistor the combination comprising a cylindrical housing having a closed end provided with a bearing support for a shaft, a resistance element formed of a flat strip of insulation wound with spaced resistance wire, said element being located against the inside cylind-

rical wall of said casing, a split ring of insulation mounted against said housing end and against said resistance element, and means engaging the split of said ring for expanding said ring to retain said resistance element against the inside of the cylindrical wall of said casing.

2. A variable resistor construction comprising a cylindrical housing having an end wall, a resistance element formed of a flat strip of insulation wound with spaced resistance wire, said element being located against the inside cylindrical wall of said casing, a split ring of insulation mounted against said housing end and against said resistance element, and means for expanding said ring to retain said resistance element against the inside cylindrical wall of said casing comprising a wedge engaging the split in said ring.

3. The variable resistor construction comprising a cylindrical housing having an end wall containing a threaded aperture, a resistance element formed of a flat strip of insulation material wound with spaced resistance wire, said element being positioned against the inside cylindrical wall of said casing, a split ring of insulation material mounted against said housing end and against said resistance element, and means for expanding said ring to retain said resistance element in position comprising a wedge engaging the split in said ring, and a screw passing through said wedge and the threaded aperture of said end wall.

4. The method of manufacturing a variable resistor having a cylindrical housing, a cover, a resistance element mounted on an insulated strip, a brush assembly therefor, and an insulated retaining ring comprising the steps of baking said strip and said ring for about one-half hour at a temperature of at least 212° F., coating with varnish said resistance element, said retaining ring, said brush arm assembly and the inside of said housing and said cover, baking said coated elements for several hours at a temperature of approximately 275° F., varnishing the inside cylindrical wall of said housing, inserting said resistance element against said wall, varnishing said retaining ring and inserting it against said resistance element, baking said assembled housing, resistance element and retaining ring for several hours at approximately 275° F., inserting said brush assembly, varnishing the edges of said cover, applying said cover, varnishing the outside of said housing and cover, and baking the assembled variable resistor for several hours at approximately 275° F.
